UNITED STATES PATENT OFFICE.

ANDREW HOWARTH AND FRANCIS A. HOWARTH, OF OXFORD,
MASSACHUSETTS.

BURR AND SHIVE EXTRACTOR FOR CARDING-MACHINES.

SPECIFICATION forming part of Letters Patent No. 495,413, dated April 11, 1893.

Application filed March 17, 1892. Serial No. 425,341. (No model.)

To all whom it may concern:

Be it known that we, ANDREW HOWARTH and FRANCIS A. HOWARTH, both of Oxford, in the county of Worcester and State of Massachusetts, have invented certain new and useful Improvements in Burr and Shive Extractors for Carding-Machines; and we do hereby declare that the following is a full, clear, and sufficient description of our said invention to enable those skilled in the art to which our invention belongs to make and use the same, reference being had to the accompanying drawings and the letters marked thereon, forming a part of this specification, and in which—

Figure 1. represents a vertical section of so much of a carding machine as is necessary to illustrate our said invention. Fig. 2—represents a top or plan view of a portion of the carding machine shown in Fig. 1, as will be hereinafter described. Fig. 3—represents a cross section on line 3, 3, Fig. 4, looking in direction indicated by the arrow, same figure,—scale enlarged. Fig. 4—represents a side view of a part of this machine, as will be hereinafter described,—same scale as Fig. 3. Fig. 5—represents upon the same enlarged scale—a side view of a part, together with a sectional view on line 5, 5, Fig. 3—arrow indicates direction. Fig. 6—shows a section on line 6, 6, Fig. 1, looking in direction indicated by arrow.

By our present invention many of the most serious objections to devices desired to accomplish similar results are overcome and obviated, and that too in a very simple and convenient manner.

In the drawings, Figs. 3, 4, 5 and 6 are drawn to an enlarged scale to aid more fully illustrating our improvements.

In the drawings, the part marked A, indicates the frame; B, the cylinder; a, a, the feed rolls; C, licker-in; D, the tumbler; E, the strippers; E', the workers, and E², the burr roll, and all these parts may be of the usual and well known forms of construction.

We will now describe one good and practical way of making and using our improvements in carding machines whereby burrs, shives and other vegetable matters are very effectually removed from the wool or stock in

the operating of carding, and which improvements are designed for and adapted to be quickly adjusted to the variety of stock to be manufactured into cloth.

55

In the drawings the part marked F, is a sector frame and is fastened to the inside of the frame A, by bolts f, f, which pass through its ears f', f', and securely hold said sector frame F, with its slot f², made in the arc of a circle— 60 equidistant from the axis of motion of the tumbler D. One of these sector frames F, is fastened under each end of the journal of tumbler D,—one being clearly shown in Figs.

65

1 and 2 of the drawings, and are provided in this instance, each with three bearing or supporting pieces G, held to their respective sector frames F', by bolts f⁵, which pass through the respective holes g⁴, in supporting pieces G, and slots f², in frames F, the latter being 70 recessed on their outer sides on each side of slots f², as seen at f³, and into which recesses the heads of bolts f⁵, fit loosely, but are prevented from turning when their nuts f⁴ are turned up to fasten the supporting pieces G, 75 to their frames F, in the desired positions for use, as hereinafter fully explained. It will be seen that bolts f⁵, are only adjustable laterally in the slots f², in the sector frames F, and therefore the supporting frames G, have only 80 two modes of adjustment, viz., they can be swung or turned to the right or left on their bolts f⁵, when nuts f⁴, are loosened, and also moved laterally when their bolts f⁵, are moved in the curved slots f², in the sector frames F. 85

The upper portions of supporting pieces G, are made to project inward from the ear parts g³, and are slotted or cored out to form slots or recesses to receive the ends of the comb bars H, to which are fastened the steel combs H', having teeth on their upper edges as clearly shown in the drawings. Combs H', are fastened, if desired to the comb bars H, in this instance by screws h,—the bars being recessed out to receive the combs as indicated in Fig. 95 3, so that the bar and comb will be of the same thickness as the lower part of the comb bar H, which just fills the slot g in the comb bar supporting piece or frame G. Said slot g is of sufficient depth to receive the comb-bar H 90 so fully that the lower edge of the comb will be also inclosed in the slot—especially when the

- comb is new and has not as yet been much worn off. It is important that the comb be adapted to delicate adjustment to meet the requirements of different stock, and also the grinding 5 off of the tumbler teeth, as well as the wearing of the comb teeth. Either end of the comb bar H, can be adjusted up or down by means of the adjusting screws g', and when so adjusted can be securely held in such adjusted 10 position by turning in the comb bar holding screws g²,—screws g', pass up through the under portions of supporting pieces G, and act upon the lower edge of the comb bar H, as it rests in the recesses g, while screws g², by 15 their gravity pass through the side of supporting piece G at the back of the comb bar and press against the comb bar H, so as to clamp the comb H' strongly against the opposite wall of the slot g: hence the screws h are not 20 absolutely necessary when the comb is new or wide. By this combination of devices the teeth of the comb H', can be set in very nicely adjusted positions in relation to the ends of the teeth on the tumbler D.
- 25 In Fig. 1, three combs H', with their supporting, holding and adjusting mechanism are thrown arranged in position to work in combination with the tumbler D, to remove the shives and burrs from the wool as it passes 30 from the licker-in to the tumbler and from that to the carding cylinder B, and which are not displaced and detached by the burr roll E². As the tumbler D, revolves the shives, burrs and other vegetable substances are 35 arrested by the teeth of the combs H' separated from the wool stock, and thrown off, and drop or fall on the floor below or into a proper receptacle provided for that purpose. If the burrs and shives are not removed before the 40 stock is worked into cloth the value of the cloth is greatly lessened unless much time is expended in removing the burrs and shives by hand labor, which is slow and expensive.
- 45 Our improvements enable the operator to quickly adjust the comb or combs to act in the most effectual manner in combination with the tumbler teeth in detaching and knocking off the burrs, shives and other ob-jectionable matter.
- 50 Different stock requires the comb or combs to be differently adjusted. In some stock the burrs and shives will be partially detached by the first comb, adjusted for that purpose, and the operation completed by the next comb 55 or combs. In some cases the combs will not all be pointing to the center of the tumbler, but one or more may be turned to the right or left of such a position, and our improvements enable the operator to nicely adjust 60 the combs as may be desired, and that too in a little time.

Our improvements may be employed, in part, in the Groves machine, patented Au-gust 11, 1891, in which case the combs would be adjustable, as in our machine.

65

What we claim, and desire to secure by Let-ters Patent, is—

1. In a carding machine, the combination with the main frame, and the tumbler-roll; of a sector-frame secured to the inner face of 70 each side bar of said main frame and having a longitudinal slot struck on an arc around the axis of said roll, the outer face of said sec-tor-frame being recessed each side of the slot, a comb, a bar to which the comb is attached, 75 a supporting piece for each end of the bar, said piece having a vertical, perforated ear, and a bolt whose head rests in said recess, whose shank passes through the slot and per-foration, and whose nut bears against the in-80 ner face of said ear, all as and for the pur-pose set forth.

2. In a carding machine, the combination with the main frame, and the tumbler-roll; of a sector-frame secured to the inner face of 85 each side bar of said main frame and having a longitudinal slot struck on an arc around the axis of said roll, the outer face of said sec-tor-frame being recessed each side of the slot, a comb, a bar to which the comb is attached, 90 a supporting piece for each end of the bar, said piece having a vertical, perforated ear, a bolt whose head rests in said recess, whose shank passes through the slot and perforation, and whose nut bears against the inner face of 95 said ear, said piece further having an upright recess in its body and within which the end of the comb-bar rests by gravity, and an ad-justing screw passing upward through the bot-tom and a holding screw passing laterally 100 through the side of said recess against the comb-bar, as and for the purpose set forth.

3. In a carding machine, the combination with the main frame, and the tumbler-roll; of a comb, a bar having a recess in its face in 105 which the comb is seated, a supporting piece for each end of the bar, said piece having an upright slot in its body into which the end of the comb-bar and lower edge of the comb are seated, an adjusting screw passing upward 110 through the bottom and a holding screw pass-ing laterally through the side wall of said slot against the back of the comb-bar, said piece further having an ear, and means for adjust-ably connecting the ear with said frame, as 115 and for the purpose set forth.

ANDREW HOWARTH.
FRANCIS A. HOWARTH.
